(57) **CLAIM**

The ornamental design for a powered air purifying respirator, as shown and described.

DESCRIPTION

FIG. 1 is a front perspective view of a powered air purifying respirator showing my new design;

FIG. 2 is a front elevation view of the powered air purifying respirator of FIG. 1;

FIG. 3 is a rear elevation view of the powered air purifying respirator of FIG. 1;

FIG. 4 is a left side view of the powered air purifying respirator of FIG. 1;

FIG. 5 is a right side view of the powered air purifying respirator of FIG. 1;

FIG. 6 is a top view of the powered air purifying respirator of FIG. 1; and,

FIG. 7 is a bottom view of the powered air purifying respirator of FIG. 1.

The broken lines shown in the drawings represent portions of the powered air purifying respirator that form no part of the claimed design.
